DAMPENING DEVICE FOR LITHOGRAPHIC
OFFSET PRESSES AND THE LIKE

Joseph Schultz, Cleveland, Ohio

Application December 26, 1930, Serial No. 504,786

36 Claims. (Cl. 101—148)

My invention relates to dampening devices, and more particularly to mechanisms of this class suitable for supplying moisture to lithographic, printing and other reproducing and typographical apparatus. The particular embodiment of this invention disclosed in the present application illustrates this invention applied to a lithographic offset press.

This present invention is a continuation in part 10 of the application on which Patent No. 1,812,720 entitled Dampening device, was granted to me June 30, 1931. The present invention is likewise a further development of the subject matter disclosed in my pending application entitled Dampening device for lithographic offset presses or the like, application Serial No. 386,573 filed August 17, 1929. It should further be noted that certain features disclosed but not claimed herein, are claimed in my co-pending Application Serial No. 507,096, entitled Dampening mechanisms for lithographic offset presses or the like, filed January 7, 1931.

Certain developments of the subject matter disclosed in this application are shown in detail 25 and are claimed in Patent No. 1,958,593, issued to me May 15, 1934.

As is well known, in the art of lithography, and especially in offset lithography, a certain amount of moisture is required to maintain the 30 printing plate adequately dampened to produce satisfactory results. It is also well known that a certain minimum amount of moisture must be continuously supplied to this plate to prevent it from becoming coated with ink and irreparably 35 damaged. It is further a fact, that different portions or zones of the plate require various amounts of moisture, these different requirements arising from differences in the size and design of the printing areas, or from the entire absence of 40 printing areas on the plate. It is also essential to point out that, when the borders of the areas which require additional moisture and those which do not, are clearly marked, a substantial 45 excess or insufficiency of moisture on either side of the border of the areas will produce imperfect work. It is also well known that any excess of 50 moisture supplied to any areas above that required, will be damaging, and further that the moisture supplied to any area must be uniformly distributed in the area in which the moisture is required.

The type of dampening apparatus which has been found satisfactory by long period of use and which has been approved and almost universally 55 adopted for lithographic offset presses comprises a reservoir of water or suitable liquid in which a water roller is partially immersed. Adapted for intermittent contact with this water roller is a ductor roller which transfers the liquid from 60 the water roller to an intermediate roller. This

intermediate roller transfers the liquid to a plurality of dampening rollers which in turn distribute the liquid to the plate on the plate cylinder, by contact. This usual and well known distributing device is intended to supply a uniform 65 amount of moisture over the entire maximum width of the plate cylinder.

It will be evident that such a uniform distribution of moisture is difficult to obtain because of unequal contacting pressure and consequent 70 unequal moisture transferring capacity at different points along the length of the rollers. This defect may occur between any of the rollers which perform the moisture transferring function. This unequal contacting pressure and consequent 75 unequal liquid transfer may result from slight variations or irregularities in the diameter of any of the rollers, unequal adjustment of the two ends of adjacent rollers, spring or deflection of the center of any roller under pressure, va- 80 riation in the water absorbing capacity of the roller covering, partial ink or grease coating on the covering, etc. It should be interpolated that with this generally used apparatus, in some cases when it is desired to reduce the amount of moisture transferred by the center of the rollers, it has been necessary to press the ends of the rollers 85 so tightly together that the rollers become dry and collect ink from the plate, especially in the case of long rollers.

It should be noted that, even if the present dampening apparatus did distribute the liquid uniformly, this would still not be the desired condition for many cases in modern high speed printing. It is well known that those portions 90 of the plate which take the heaviest amount of ink will also need a heavier amount of dampening liquid than the portions taking a relatively lesser amount of ink, or no ink at all. When the liquid is supplied in a uniformly distributed 100 manner to such a plate with the usual apparatus above referred to, the heavily inked portions will either not receive sufficient moisture or the lightly inked portions will receive an over supply of moisture. An over supply of moisture, 105 to any portion of the plate results in an uneven color and a lack of uniformity of color on the printed sheet. A deficient amount of moisture on any portion of the plate will cause a filling in with ink, or, what is known in this art as 110 "catching up".

With the present dampening apparatus it is necessary for the pressman to continuously watch his plate. In order to correct the weak spots which are deficient in moisture, the pressman 115 supplies more moisture to the entire width of the plate than is required, and thus overcharges certain other portions. If he does not do this it will be necessary for him to manually add water with a sponge to the dampening rollers 120.

at those places where more water is required. In an effort to overcome these difficulties and in order to insure the provision of sufficient liquid for the different areas of the plate without over-charging any portion of the plate, I have developed and successfully applied the apparatus to be hereinafter described.

The general object of my invention is to provide a device for supplying moisture to lithographic offset presses or similar printing apparatus, which may be adjusted to satisfactorily supply moisture to all portions of the plate used on the press and in proportion to the requirements of each particular portion of the plate.

15 A further object of this invention is to provide apparatus of this type which can be depended upon to maintain the same rate of feed of water after having once been adjusted to suit the requirements of the plate in the press, and which further makes it unnecessary for the operator to continuously watch the moisture condition of the plate.

20 A further object of this invention is to provide means whereby a controllable quantity of moisture may be supplied directly to one portion or zone of the plate without affecting the moisture condition of the laterally adjacent portion or zone of the plate.

25 A further object of this invention is to provide apparatus which comprises elements adapted to supply a uniformly distributed minimum amount of moisture to the plate throughout its entire width together with means adapted to vary this uniformly distributed amount of moisture, and additional elements adapted to add variable amounts of moisture in accordance with the requirements of the surface of the printing plate.

30 A further object of this invention is to provide apparatus of this type which will permit of quick and dependable regulation of the amount of supplemental water fed to any point or zone of the dampening device.

35 A further object of this invention is to provide a plurality of liquid feeding elements which will feed very small amounts of liquid and which will permit a close regulation of variations in the feeding of these small quantities of liquids.

40 A further object of this invention is to apply the principle of capillarity for feeding liquid to the dampening apparatus in such a manner to accomplish the aforementioned objects.

45 A further object of this invention is the provision of a device involving the principle of capillarity in which the flow of liquid through any one element of the group of elements can be instantly interrupted.

50 A further object of this invention is to so arrange the supplemental feeding means that any one of the individual liquid supplying devices may quickly be replaced individually without disturbing any of the adjacent supplemental liquid supplying devices.

55 A further object of this invention, ancillary to the foregoing, is to provide means for keeping the dampening rollers and apparatus free and clean from ink, thus eliminating the need for frequent cleaning of these rollers and concomitant wear and expense.

60 A further ancillary object of this invention is to prevent wear and tear on the dampening rollers due to excessive pressure on these rollers, thus reducing the maintenance cost on these parts as well as eliminating the expense and delay incidental to the repair, replacement and renewal of these dampening rollers.

A further ancillary object of this invention is to insure longer life for the plate of the press due to the provision of the proper amount of moisture for every portion of the plate which eliminates the deleterious results from filling in with 80 ink on the one hand due to an insufficiency of liquid and the overcharging of acid water on the other hand with an excess of liquid.

A further ancillary object of this invention is to speed up production of a satisfactory product 85 from the press.

A further ancillary object of this invention is to prevent the accumulation of excess acid water on the ends of the ink rollers and the consequent etching of these ink rollers so that they will not 90 take ink, thus avoiding the necessity of counter-etching these rollers again so that they will take ink.

A further object of this invention is to provide an apparatus of this type which can be applied 95 to presses now in use as well as to new presses and which can be quickly and easily attached to such presses.

Further objects and advantages of this invention will appear from the following description 100 and from reference to the accompanying drawings. These annexed drawings and description set forth in detail certain means embodying this invention, such disclosed means constituting however, but a few of the forms in which the 105 principle of this invention may be applied.

In said annexed drawings: Figure 1 is a view, mainly in side elevation, showing my improved apparatus applied to a standard type of lithographic offset press, a portion only of the press 110 being illustrated, and certain parts being shown in section to more clearly disclose my invention.

Figure 2 is an enlarged partial perspective view showing my invention as applied to a dampening apparatus of the usual type on a standard lithographic press, such as illustrated in Figure 1.

Figure 3 is a fragmentary front elevational view of the apparatus shown in Figure 1 this view being taken from the plane indicated by line 3, 3 in Figure 1.

Figure 4 is an enlarged fragmentary sectional view taken in the plane indicated by line 4, 4, Figure 7, and showing the details of a device for regulating the water level in a certain reservoir.

Figure 5 is a plan view of the parts shown in Figures 1 and 3.

Figure 6 is a fragmentary rear elevational view of the parts shown in Figure 1, this view being taken from the plane indicated by line 6, 6 in Figure 1.

Figure 7 is an enlarged cross-sectional view taken in the plane indicated by lines 7, 7 in Figures 3, 5 and 12 showing my invention applied to a dampening apparatus of a usual type and showing certain parts of my invention in their 30 position of maximum liquid transferring capacity.

Figure 8 is a view similar to a portion of Figure 7 showing these certain parts in a position of less liquid transferring capacity than that shown in Figure 7.

Figure 9 is another view similar to a portion of Figure 7 but showing the parts in which they do not transfer any liquid.

Figure 10 is an enlarged fragmentary plan 145 sectional view taken from the plane indicated by line 10, 10 in Figure 9.

Figure 11 is an enlarged view of a portion of Figure 7, this view being taken from the plane indicated by line 11, 11 in Figure 10.

Figure 12 is a sectional view through the center of a trough and other novel elements illustrated in Figures 7, 8 and 9, this section being taken in the plane indicated by lines 12, 12 in 5 these figures.

Figure 13 is a detached fragmentary sectional perspective view of the trough element illustrated in Figures 7, 8, 9 and 12.

Figure 14 is a detached perspective view of one 10 of a plurality of elements which is mounted for sliding engagement in the trough shown in Figure 13.

Figure 15 is likewise a perspective view of the 15 element illustrated in Figure 14, viewed from a different angle.

Figure 16 is a detached perspective view of one 20 of the composite liquid transfer or wick elements, showing also the spring which is attached to this wick element and which operatively connects the wick element with the part illustrated in Figures 14 and 15.

Figure 17 is an elevational view of the parts 25 illustrated in Figure 16, these parts being shown in a flat position.

Figure 18 is a longitudinal sectional view taken 30 through the lower portion of the composite liquid transferring element illustrated in Figure 16.

Figure 19 is a detached perspective view similar 35 to Figure 16, of a modified form of liquid transfer or wick element.

Figure 20 is a fragmentary perspective view 40 similar to a portion of the part shown in Figure 15 modified for co-operation with the element shown in Figure 19.

Figure 21 is a cross sectional view of a modified 45 form of this invention embodying its broad features, this view being similar to Figure 10 in my Patent No. 1,812,720, referred to hereinbefore.

Figure 22 is a perspective view of one of the 50 elements shown in Figure 21, and corresponds with Figure 11 in my Patent No. 1,812,720.

The liquid used for dampening the plate of a 55 lithographic offset press is usually either water or a relatively dilute solution of acid in water, or a dilute solution of gum arabic or other materials or combinations of materials in water, 45 depending upon the requirements. In the following specifications the term water, moisture and liquid are used interchangeably and it is understood, that these terms are to include such liquids as are referred to above, or any liquids which may be used with this apparatus for the purpose set forth.

In the drawings only so much of a lithographic 60 offset printing press is illustrated as bears direct relation to this invention, and to its location on the press and operation with the press. The drawings illustrate one form of this invention in several assembled views on the press and also in detail, and the drawings further illustrate several modified forms of this invention in detail, in order to show the breadth and scope of this invention.

I shall first describe the form of the invention 65 which is illustrated in Figures 1 to 18 inclusive. In these figures, and with particular reference to Figures 1, 3, 5 and 6, 1 indicates the frame of the press, upon which are mounted, in well known manner, a paper or printing cylinder 2, blanket cylinder 3, and plate carrying cylinder 4. These cylinders are rotated by suitable gears 5, 6 and 7 respectively, which are driven by suitable power driven gearing, not shown. The printing plate 8 is mounted on the plate carrying cylinder 4, 70 in the usual manner. Inking rollers 9 are suit-

ably mounted for peripheral contact with the printing plate 8 as clearly shown in Figures 1, 5 and 6. The balance of the inking mechanism including ink fountain, ink distributing rollers and controlling mechanism are not shown, as these devices are well known to those skilled in this art and have no special bearing on this invention.

Referring now to Figures 1, 2 and 7, a usual 80 type of dampening device, such as has generally been adopted for use on lithographic offset presses, and as shown in the drawings, will now be described.

Two dampening rollers, 10, 10, are mounted on the frame of the press for peripheral contact with the plate 8. These dampening rollers 85

10 are usually covered with molleton, and are preferably so mounted that they contact one or more of the intermediate or distributing rollers 11, frequently mounted for axial reciprocation, one such roller 11 being shown in the drawings.

Adjacent to this distributing roller or rollers 11, 90 is mounted a ductor roller 12, preferably covered with molleton, which is oscillatorily mounted to intermittently and alternately contact the distributing roller 11 and a water roller 13. This water roller 13 is mounted on a shaft 14 located

above a pan or reservoir 15 adapted to contain 100 water or other suitable liquid. This pan is removably supported on a pair of rods 16 and 17 running transversely of the press between the frames 1. The roller 13 is preferably covered with suitable water absorbing material 13' in

those presses in which this roller rotates at a 105 relatively slow speed, and is usually provided with a metallic surface in those presses in which this roller runs at a relatively higher rate of speed. The covering 13', when used, usually consists of a single layer of unbleach muslin, but any other suitable material or thickness of material may be used.

The roller 13 may rotate 110 either continuously or intermittently. When it rotates intermittently its rotation is usually simultaneous with its contact with the ductor roller and the amount of its rotation can be regulated.

The apparatus thus far described is quite well 115 standardized on all lithographic offset presses and its method of mounting and method of driving, while varying in some features, is well understood and need not be further described in detail. This standardized dampening apparatus

operates in the following manner. Water 120 or other liquid is usually manually poured into the pan 15. The periphery of the roller 13 being partially immersed in this bath of liquid, absorbs moisture, or conveys moisture by ad-

hesion which is transferred to the ductor roller 12 at intervals. This ductor roller, in turn, 125 transfers this liquid to the roller 11 which distributes the moisture to the dampening rollers 10, whence it is applied to the plate 8. It will

be apparent that the intention of this device is 130 to transfer a uniformly distributed amount of moisture to the plate and across the entire face thereof. Means are also provided for regulating the intensity of the pressure exerted by the

ductor roller on its two adjacent rollers and for aligning this ductor roller therewith and for 135 aligning and regulating the pressure exerted by the other rollers upon each other. It will be evident that this method of liquid transfer is 140 dependent upon the perfection of the several rollers and the accuracy of their alignment, and is affected by the lack of roundness, uniform diameter, uniform absorbing power and by any

spring or elasticity of the rollers between their 145

150

supported ends. It will also be apparent that this system makes no provisions whatever for adding varying amounts of moisture to the plate on the cylinder.

5 This invention which is adapted to co-operate with and supplement the above apparatus, and remedy its deficiencies and to augment its performance, will now be described. Referring particularly to Figures 1, 3, 5 and 7 it will be noted that I have provided a pair of brackets 19 which are removably mounted on members forming a part of the standard press. The bottom of these brackets are removably seated on the tie rod 18 and the intermediate portion of the brackets are attached to the pan supporting rod 17 by means of a bracket cap 20 detachably secured to the bracket 19 by means of screws 21. As clearly shown in Figures 1 and 7, the upper portion of the bracket is formed with a vertically disposed guide portion 22, which is preferably located vertically over the standard reservoir or pan 15.

10 Referring now to Figures 1, 2, 3, 5, 7 and 12 it will be noted that I support a relatively narrow and deep trough 23 upon the bottom of the standard reservoir or water pan 15, this trough being substantially the same length as the water roller 13. This trough is formed with a front wall 24, a rear wall 25, a right wall 26, a left wall 27 (as viewed in Figures 3 and 5), and a preferably curved bottom 28. Mounted upon the front wall 24 are a pair of pockets 29. The openings in these pockets are of a suitable size and are properly located to slidably fit over the vertical guide portions 22 on the brackets 19, from which it will be evident that the weight of the trough 23 is supported by the water pan 15, and that the trough is held in vertical position by the guides 22 on the brackets 19, and that the trough may be removed from the pan by lifting it vertically.

15 For the purpose of supplying liquid to this trough 23 the right wall 26 thereof is provided with an inlet opening 30. A preferably flexible delivery conduit 31 is connected with this inlet opening, and liquid is supplied to this conduit from the gear driven pump 32 all as clearly shown, in Figure 1. This pump is supplied with liquid through the suction conduit 33 the inlet end of this conduit being submerged in a liquid storage tank 34, this inlet being preferably protected by a screen. A pressure regulating by-pass valve 35 has its inlet end connected with the delivery conduit 31 and its outlet connected with a by-pass conduit 36 which discharges into the reservoir 34.

20 The upper edge of the left wall 27 of the trough 23 is of slightly less height than the other walls of this trough, as clearly shown at 37 in Figure 12, this lowered edge serving as an overflow for the liquid in the trough 23. Secured to the trough immediately below this overflow is an overflow cup member 38 which is adapted to catch the liquid which flows over the top of the wall 27 at 37 and deflect it so that it runs downwardly along the left end of the front wall 24 into the pan or reservoir 15 in clear view of the operator as shown in Figure 3. As shown in Figures 1, 3 and 4, the pan 15 is provided with an outlet 39. This outlet is provided with a vertically adjustable sleeve member 40 which is adapted to regulate the level of the liquid in the pan. Any liquid above this level will pass over the lip of the sleeve member 40 into the overflow conduit 41 whence it passes into the storage tank 34.

25 previously referred to, all as clearly shown in Figure 1.

30 References to Figures 1 and 7 to 18 inclusive, will disclose an anchoring plate 42 mounted on the rear wall of the trough 23 extending for substantially the full length of the rear wall. The upper end of the front wall is formed with a horizontally projecting shelf 43 preferably formed by attaching an angle to the front wall 24. Removably mounted on this horizontal shelf are a plurality of detent guide plates 44 which are secured to this shelf by screws 45. The greater portion of these detent guide plates are vertically above the horizontal shelf 43, as clearly shown in Figures 10 and 11; however, a guide lip 46 and a detent tooth 47 project inwardly toward the center of the trough for a purpose to be hereinafter pointed out.

35 Mounted for insertion vertically into the trough 23 are a plurality of spring fingers 48 formed with two legs 49 and 50. Reference to Figures 2, 3, 5 and 12 will disclose the fact that a relatively large number of these fingers are inserted in the trough preferably contacting each other laterally and extending substantially for the full length of the 100 trough. These spring fingers are preferably all identical in size and form. The leg 50 of the spring finger is formed at its upper end with a lip 51 adapted to facilitate the gripping of the spring finger 48 for vertical movement in the trough. 105 The front leg 50 of this spring finger 48 is further provided with a notch or cut out portion 52 and with a series of teeth 53. The lower end 54 of the spring finger is preferably curved and of a form simulating the curved bottom 28 of the 110 trough 23. This lower end 54 of the spring finger is provided with one or more perforations 55. The upper end of the leg 49 is formed with a curved lip 56 forming a smooth upper surface and adapted to fit over the upper end of the rear wall 25 of 115 the trough 23.

40 Figures 16, 17 and 18 are detached views of a novel siphon capillary wick element which is designated in its entirety by the numeral 57, and which is provided for co-operation with the spring 120 finger 48 and with the trough 23, for the purpose of transferring water in the desired amounts from the trough to the water roller 13. The water conducting element consists of a strip of molleton indicated at 58 and tapered at one end as clearly 125 shown at 59. A portion of this tapered end is enclosed in, and secured to, a holding pocket 60 forming a part of a thin flexible metallic backing element 61. It should be here noted that this metallic backing element for the wick is shown 130 considerably heavier in the drawings, for the purpose of clearness, than the element which I use in practice, the element actually used preferably consisting of a strip of thin brass three thousands of an inch in thickness. Attached to the lower 135 end of the holding pocket 60 as shown in Figures 16, 17 and 18 is one end of a relatively light coil tension spring 62, the other end of which is adapted to be threaded through the perforations 55, in the lower end of the spring finger 48. The 140 metallic backing element 61 is further provided with a perforation 63 near its upper end and with two relatively smaller perforations 64 as shown in Figure 16. The perforation 63 is used for attaching the upper end of the metallic backing member to the anchoring plate 42 by means of screws 65 which engage threaded openings 66 in this anchoring plate. Staples 67 are passed through the molleton 58 and through the perforations 64 145 150

in order to removably connect the molleton and the backing element, at this point.

The spring fingers 48 and siphon capillary wick elements 57 are assembled in the trough as clearly shown in Figures 7 and 12, from which it will be evident that the outer end 58^a of the wick or molleton 58 rests upon substantially the top of the water roller 13, and that the inner end of this wick element is yieldingly held immersed in the liquid in the trough. It will be understood that the detent guide plates 44 on the horizontal shelf 43 and the threaded openings 66 in the anchoring plate 42 must be equally spaced and must each be in the proper opposed position to permit aligned 10 mounting of the spring fingers 48 and siphon capillary wick elements 57 in the trough 23.

Functioning of siphon capillary wick element

The functioning of one of the siphon capillary wick elements 57 will now be described, and can best be understood by reference to Figures 7 to 12 inclusive. Figure 7 illustrates the position of the wick element 57 in which that portion of the molleton located interiorly of the trough 23 is immersed in the liquid to the maximum depth. When the molleton is in this position water will be absorbed by the immersed portion of the molleton 58^x (Figures 7 and 12) and will be drawn upwardly by capillary attraction to that portion 71 of the wick element resting on the curved lip 56 of the spring finger 48 and will thence be drawn downwardly by a combination of capillary and siphon action until it reaches the water roller 13 upon which the water will be deposited. In 20 the position of the parts illustrated in Figure 7, the molleton will transfer the maximum amount of water from the trough 23 to the water roller 13. When the spring finger 48 is raised in the trough, the curved lip 56 forces the elevated section 25 or high point 71 of the wick element upwardly, which draws the tapered end 59 upwardly, due to the fact that the other end of the wick is fixed to the anchor plate 42. Thus the tapered end 59 of the molleton is raised in the water and, after a sufficient vertical movement of the spring finger, may be only partly immersed in the water in the trough 23, as shown by the position of this molleton at 59^x (Figures 8 and 12). When the molleton is in this position it will be evident, first, 30 that a smaller portion of the molleton is immersed in the liquid and second that the cross sectional area of the molleton which is capable of absorbing water from the surface of the liquid and transferring it upwardly, is substantially reduced due to the tapered end of the molleton 58, and third, 35 that the liquid must travel a considerably greater distance in order to travel to the high point 71 of the wick on the bead 56 of the spring finger. All of these features will tend to reduce the flow 40 of liquid in the molleton and the amount of reduction in the liquid transferred from the trough to the water roller will vary with the variation in the depth of the immersion of the tapered end of the molleton in the liquid of the trough. When 45 it is desired to still further reduce the flow of liquid the spring finger 48 may be still further raised in the trough until the holding pocket 60 only is immersed in the water as shown at 60^x (Figure 12). This holding pocket, being formed 50 of non-absorbent material, restricts the passage of the liquid to the molleton, this arrangement permitting the flow of liquid to be reduced to one or two drops per minute when the holding pocket 55 is very slightly immersed in the liquid. It will further be understood that if the spring finger is

still further raised so as to entirely remove the wick and holding pocket from the liquid in the trough as shown at 60^y (Figures 9 and 12) for instance, that no liquid will flow to the molleton and no liquid will be transferred to the water roller 13.

The spring finger 48 readily can be inserted in the trough 23 by manually pressing the grip 51 and bead 56 toward each other, whereupon the spring finger may be vertically moved in the trough, this vertical movement being limited only by the engagement of the guide lip 46 with the upper and lower edges of the notch or cut out portion 52 on the leg 49. The guide lips on two adjacent detent guide plates will serve to space and vertically guide the intermediate spring fingers. The elasticity of the spring finger will hold the leg 50 between the guide lips 46 and will also press the tooth portion 53 against the detent tooth 47 on the detent guide plate 44, and the engagement of the detent tooth 47 with any one of the teeth 53 will hold the spring finger 48 in any desired position vertically in the trough which will, in turn, hold the wick element in its adjusted position. When it is desired to readjust the wick element upwardly or downwardly in the trough it is only necessary to press the grip 51 of the spring finger so that the leg 50 will move slightly away from the detent teeth 47 and move the finger to the desired position and release it, whereupon the elasticity in the finger will hold one of its teeth 53 in engagement with the detent tooth 47. It will be evident that the tension of the spring 62 will keep the wick element 57 taut, for any position of the spring finger 48 and that the flexible metallic backing element 61 will prevent the stretching of the molleton 58, and will not interfere with the flexing of the wick element around the curved lip 56.

Operation of complete apparatus

The moisture circulation and supply system can best be understood by reference to Figures 1, 3, 4 and 7 and operates as follows: Water or a suitable liquid solution is poured into the liquid storage tank 34. This liquid is sucked from this tank through the suction pipe 33 by the pump 32 which, in turn, delivers the liquid through the delivery conduit 31 into the trough 23 through the inlet opening 30. When this trough has been filled up 120 to the level of the top 37 of the left end wall 27, the liquid overflows through the overflow cup member 38 into the pan or reservoir 15. Any liquid which rises in the pan above the level of the top of the sleeve member 40, overflows through 125 the outlet 39 into the overflow conduit 41 and discharges into the liquid storage tank 34. The regulating valve 35 forms a means for controlling the amount of liquid which is supplied to the trough 23 by the pump 32. This valve together 130 with the conduit 36 forms a by-pass for the liquid which is delivered by the pump. It will be understood that, when the valve is so regulated that its resistance to the passage of liquid is small, a relatively large proportion of the liquid will travel 135 through this by-pass and a relatively smaller portion will be delivered to the trough 23, and conversely. It will be understood that a sufficient amount of water is constantly fed to the trough 23 to maintain the liquid level with the top 37 140 of the wall 27 and preferably so that a slight overflow will be maintained over the top 37.

Referring now to the transfer of water to the plate, the periphery of the water roller 13, being 145 partially immersed in the liquid in the pan 15, 150

will absorb or collect moisture by adhesion to its surface. This moisture is carried upwardly as indicated by the arrow "X" shown in Figure 7, and thence downwardly as indicated by the arrow "Y", whence it is periodically transferred to the ductor roller 12 and is finally transferred to the plate 8 through the intermediate roller 11 and dampening rollers 10, as hereinbefore described. Moisture thus delivered by the water roller to the plate in accordance with my invention, is intended to be the minimum of moisture required for uniform distribution to the plate. The amount of moisture absorbed or collected by the periphery of the roller 13 will depend upon the speed of rotation and upon the depth of immersion of the periphery of the roller in this liquid. Apparatus is provided in standard presses for controlling the speed of rotation of the roller and I have provided means for regulating the depth of immersion of the roller by the provision of the adjustable outlet sleeve member 40 on the outlet 39, as shown in Figure 5. The range of regulation possible with this device is from a very slight immersion to an immersion amounting to nearly one third of the periphery of the roller, thus providing for ample range for the minimum or nominal amount of uniformly distributed moisture supplied to the plate.

As explained above, it is found in practice, that some parts of the printing plate require more water than other parts. For purposes of explanation the different types of areas on the surface of the plate 8 have been illustrated in Figures 3, 5 and 6 by different types of shading, for instance, the two portions or zones 8^a, which require a relatively very heavy amount of ink are shown in black. Between these zones 8^a is a portion or zone 8^b which requires relatively somewhat less ink than the portions 8^a and which for purposes of comparison is indicated by finely spaced criss cross shading. Adjacent to, and outwardly from the zones 8^a are shown portions or zones 8^c which require relatively very little ink and which for purposes of comparison are indicated by light open criss cross shading. At 8^d are shown portions of the plate which require no ink at all and which are shown blank. Portions of the plate cylinder which are not covered by the plate are indicated at 4^e.

It will be understood that generally speaking, the amount of moisture which it is necessary to supply to a particular portion of the plate will vary with the increase in the amount of ink taken by said portion of the plate and, in fact, the variation will be substantially in proportion to the relative amounts of ink used. It should also be understood that the distribution of the moisture in any zone, be it wide or narrow, must be uniform, as the presence of any lack in uniformity in moisture distribution will result in defective work. It is also essential to note that the moisture must be closely confined within the zones in which it is required for the best results and that the borders of these zones are frequently very clearly marked.

For those plates, or for those portions of the plates, where the moisture distribution on the plate 8 effected by the dampening apparatus with the water transferred by the water roller 13 from the pan 15, is sufficient and satisfactory, no further liquid need, of course, be supplied to the water roller.

Where no additional water is required by the printing plate the siphon capillary wick elements 57 are adjusted to the position shown in Fig-

ure 9. In this position the molleton 58, having all portions thereof located above the surface of the water in the trough 23, will deliver no water to the water roller 13, and, in riding on the roller 13 will assist in spreading the water uniformly over the surface.

For those portions of the plate which require additional water, either because of the inability of the dampening system to supply a uniformly distributed coating of liquid to the plate or because of the variation in the requirements of the different portions of the plate, the operator will determine the position on the water roller 13 which corresponds with the position on the plate at which additional water should be supplied. It is sometimes difficult to correctly select the place on the water roller at which this additional water should be supplied, due largely to the distance of the printing plate from the water roller.

To assist the operator in selecting exactly the correct place for this additional water a bar 69 is mounted on the rear of the machine adjacent to the printing plate. Attached to, or mounted upon this bar, in any desired manner are a plurality of indices or numerals 70. These numerals are preferably equally spaced and this spacing is identical with the spacing of the spring fingers 48 in the trough 23. Indices or numerals 68 are further stamped or otherwise suitably marked on the spring fingers 48 as clearly shown in Figures 3 and 15 and, in fact, each numeral on the spring fingers 48 is exactly in line longitudinally with the corresponding number on the bar 69. It will accordingly be evident that if the operator notes, for instance, that additional water is required at the position on the plate indicated by numerals 13 to 18 inclusive on the bar 69, that the spring fingers numbered 13 to 18 inclusive ought to be manipulated to supply this additional water. The amount of water furnished for each particular place which requires additional water can be regulated by raising or lowering the spring finger 48 thereby varying the depth of immersion of the molleton 58 in the liquid in the trough 23 as previously described.

This additional water, it should be pointed out will be uniformly spread throughout the entire width of the molleton or distributing element 58 but that it will not spread beyond this width. The roller 13 will accordingly receive a uniformly distributed coating or zone of liquid supplied to it by the depending end of the molleton riding on the roller. It should also be pointed out that this liquid is supplied to the roller 13 at a point substantially at the top of its periphery and in such position that the liquid will not return by gravity down the upwardly travelling portion of the periphery of the roller, and that all of this supplemental liquid will thus be carried downwardly along the portion "Y" (Figure 7) of the periphery of the roller for transfer to the dampening rollers and plate 8. In this manner I supply a substantially uniformly distributed normal or minimum of moisture to the printing plate and supplement this by additional moisture when and where required and in uniformly distributed condition where applied. In practice a slight amount of space is provided between adjacent wicks 58 so that liquid from one wick will not pass to the adjacent wick by contact.

Figure 2 illustrates the variations in the positions occupied by the upper points of the siphon capillary wick elements while the discharge ends of these wicks remain fixed with relation to the roller 13. Figure 3 illustrates the position of

the spring fingers 48 to produce the proper feeding positions of the wick elements 57 to satisfy the requirements presupposed for the printing plate and represented by shaded areas in Figure 3.

5 I have found as a result of many experiments that the flow of liquid in molleton is continuous and flows at an accurately uniform rate for a long period of time, providing that the water level and other conditions remain substantially uniform. I have further found that the presence of lint, or other fine particles in the water do not substantially interfere with the uniform functioning of the siphon capillary action in the molleton.

15 One of the advantages of this invention is its capacity for keeping the dampening rollers clean and free from dirt, grease and ink. In some instances I have even found that rollers which were partly coated with ink collected from the plate 20 due to an insufficient supply of moisture, have become cleaned of all ink and grease after my invention was applied. This result is due to the maintenance of proper moisture distribution.

25 While it is a fact that the covered rollers of standard dampening devices and particularly water rollers, must frequently be re-covered or replaced, I have found that these rollers can be maintained in service for a comparatively long period of time without becoming defective when 30 my improved device is co-operatively associated therewith.

The purpose of the modification in the wick element 57^a shown in Figures 19 and 20 will now be explained. As is well known to operators of 35 lithographic printing presses, it is very essential that nothing except the paper be permitted to pass between the different rollers and cylinders and that any article caught between the rollers or cylinders causes serious damage. The wick elements are secured against dislodgment by the 40 screws 65 in the anchoring plate 42 and by the connection of the spring element 62 to the bottom 54 of the spring finger 48, which is, in turn, locked in the trough 23. In the event that the wick elements accidentally become disengaged from the 45 finger 48 and from the anchoring plate 42, I provide a further means for holding the wick element to the spring finger. This means consists of a T shaped head 72 secured in any desired 50 manner to the leg 49 of the spring finger 48 and formed with a stem 72^a and, when this metallic backing element is sprung and caused to slip over the head 72 the slot 73 has sliding engagement with the stem 72^a and will not become detached 55 therefrom. The slot 73 is of sufficient length to permit the free movement of the wick element, over the curved lip 56, for the desired range of 60 adjustment of the wick. If, for any reason, the connection between the wick element 57^a and the spring 62 or the connection between the spring 62 and the finger 48 becomes disengaged, the wick element 57^a slides vertically on the T head 72 until the bottom 73^a of the slot 73 abuts the head 72 whereupon no further movement of the 65 wick element takes place. This wick element is thus prevented from falling and becoming entangled in any of the working parts of the press located therebeneath. This safety feature is operative whether or not the wick element maintains its connection to the anchoring plate 42.

70 Figures 21 and 22 illustrate an early modified form of this invention, being a reproduction of Figures 10 and 11 of my Patent No. 1,812,720, with which the present application was co-pending in 75 the Patent Office. Referring to these figures, the

auxiliary reservoir or trough is indicated at 74, this trough being mounted on rods 75 which are in turn supported on the press. This trough is provided with an overflow 76 and a drain pipe 77. This trough is provided with a metallic lining 78 which extends over one wall of said trough forming a curved lip 79. Guided upon this lip 79 and supported on the bottom wall of the reservoir 74 is a siphon capillary wick element indicated in its entirety at 80. This siphon capillary wick element consists of a bifurcated finger 81 formed with a grip portion 82. A strip of molleton 83 is attached to the finger 81 preferably by stitching substantially near the bottom of the two legs of the finger 81 as shown at 84 and 85. The length of the molleton between the two stitched portions is so selected that the stitched portion 84 will substantially rest on the bottom of the reservoir 74 when the upper portion 86 of the molleton loosely rests on the curved lip 79. An extension 87 depending below the stitched portion 85 rests freely on the water roller 13.

It will be evident that the siphon capillary wick element illustrated in Figures 21 and 22 will operate substantially in the same manner as the corresponding elements in Figures 1 to 20 inclusive, and will transfer liquid from the trough directly to the water roller by combined capillary and siphon action. It will be apparent, however, that the wick 80 is not capable of the refined adjustment 100 for regulation of feed possessed by the wick elements 57. It is adjustable only to the extent that the wick element 80 may be held in a raised position by friction against the lip 79. On the other hand the wick element 80 is portable and may be 105 transferred from one point along the length of the roller to any other desired point, and a plurality of these wick elements 80 ordinarily suffice to add liquid to all desired portions of the roller 13, and thus to the printing plate, unless a very fine 110 graduation of moisture distribution is required.

One of the important novel features of this invention, is the means for regulation of the water absorbing capacity of the immersed portion 115 of the wick. While, in the forms of this invention described above, the regulation is effected by moving the immersed portion of the wick vertically with relation to the surface of the water by a sliding action, this invention comprehends various other methods of producing this regulation; for 120 instance, the movement of the immersed portion might be controlled by a pivotal action and the immersed portion might follow a curved or angular path with relation to the surface of the liquid.

In the present disclosure the novel feeding device is illustrated and described as the feeding of 125 water to the usual water roller, which is one element of a water distributing apparatus adapted to transfer water to the printing plate on the lithographic press. I desire to point out that this novel 130 feeding device is not restricted to operative association with the water roller but may be mounted to feed water to any one of the rollers in the usual dampening apparatus, or this device may be mounted to feed liquid to any other type of liquid 135 distributing apparatus or element, such as a belt or apron for instance, or upon any other mechanism adapted to transfer liquid to the plate without departing from the scope and spirit of my invention. In a broader aspect this novel feeding 140 device may be mounted to feed liquid directly upon the printing plate, which may, or may not have been pre-moistened by any other means for supplying liquid.

Many other modifications of this invention and 150

- its application will naturally occur to those skilled in the art, and the present disclosures should therefore be considered as typical only, and I desire not to be limited to the exact constructions shown and described.
5. What I claim is:
1. A wick element for use in a liquid feeding device comprising an absorbent member and a relatively non-absorbent flexible member, said members being attached one to the other.
  2. A wick element for use in a liquid feeding device and adapted to conduct liquid by capillarity, comprising an extensible member and a relatively non-extensible flexible member, said members being attached one to the other.
  3. A wick element for use in a liquid feeding device comprising a fibrous extensible member and a metallic flexible member, said members being attached one to the other in substantially parallel relation.
  4. A wick element for use in a liquid feeding device comprising an absorbent member and a relatively non-absorbent member, said members being attached one to the other in substantially parallel relation and said absorbent member being formed with a portion tapered in the direction of its length.
  5. In a liquid feeding appliance, a reservoir of liquid, an absorbent element mounted for immersion in said liquid, a portion of said element being wrapped in a non-absorbent member.
  6. In a liquid feeding appliance, a reservoir of liquid, a plurality of absorbent elements mounted for immersion in said liquid, a portion of each of said elements being formed with a gradually reduced cross sectional area in the direction of its immersion, each of said elements being provided with means for varying the depth of immersion of said portion, whereby the immersion of said portion of each of the elements may be varied independently.
  7. In a liquid feeding appliance, a reservoir of liquid, an absorbent element mounted for immersion in said liquid, a portion of said element being formed with a gradually reduced cross sectional area in the direction of its immersion, said portion being partially enveloped by a non-absorbent member.
  8. In a liquid feeding appliance, a reservoir of liquid, an absorbent element mounted for immersion in said liquid, and means adapted to yieldingly hold said element in said immersed position.
  9. In a liquid dispensing apparatus, a reservoir of liquid and a plurality of capillary elements each having one end immersed in said liquid and adapted to conduct liquid from said reservoir, and individual means each adapted to vary the capacity of one of the said immersed ends for absorbing liquid, independently of every other immersed end.
  10. In a liquid feeding apparatus, a reservoir of liquid, an element adapted to lift liquid by capillarity from said reservoir and feed said liquid to a point exteriorly of said reservoir and means adapted to vary the vertical distance through which the liquid is lifted by capillarity.
  11. In a liquid feeding apparatus, a reservoir of liquid and an absorbent element in the form of a siphon having two legs and a connecting top section adapted to feed liquid from said reservoir, one leg of said element being adapted to absorb liquid and the other leg of said element being adapted to deliver said liquid and means adapted to raise the top section of said element while one of said legs remains substantially stationary.
  12. In a liquid feeding apparatus, a reservoir of liquid, an absorbent element comprising two depending legs joined by an elevated section, one of said legs being adapted to conduct liquid from the surface of said liquid to said elevated section and means adapted to vary the length of said conducting leg.
  13. In a liquid feeding apparatus in combination, a reservoir of liquid, a siphon having a delivery end and an intake end, said delivery end being fixed relatively to said reservoir and said intake end being adjustable relatively to said reservoir, and means for maintaining the level of the liquid in the reservoir constant.
  14. In a liquid feeding apparatus, a reservoir of liquid provided with a wall, an absorbent element extending over said wall and adapted to conduct liquid from said reservoir, and vertically slidable means adapted to raise one end of said element while the other end remains substantially stationary.
  15. In a liquid feeding apparatus, a reservoir of liquid provided with a wall and a plurality of absorbent elements each adapted for partial immersion in said liquid and adapted to siphon liquid over said wall, said elements being relatively narrow and spaced from each other, the depth of the immersion of each of said elements in the liquid being independently adjustable, whereby the amount of liquid siphoned by each of said elements is individually controllable.
  16. In a liquid feeding apparatus, a reservoir provided with a wall, and an absorbent element having one end located interiorly of said wall and the other end located exteriorly of said wall, and means adapted to adjust the vertical position of a portion of said element intermediate said ends, and means adapted to hold said intermediate portion in its adjusted position.
  17. In a liquid feeding apparatus, a reservoir of liquid provided with a wall, a plurality of absorbent elements each having one portion depending exteriorly of said wall and having another portion depending interiorly of said wall, said interior portions adapted to conduct liquid by capillarity, and a plurality of individually adjustable means adapted, each independently of every other means, to vary the length of the portion along which the liquid is conducted by capillarity.
  18. In a liquid feeding apparatus a reservoir provided with a wall, and an absorbent element extending from the interior of said reservoir to a point exteriorly of said reservoir, the exterior end of said element being fixed relatively to the reservoir and the interior end being vertically adjustable within said reservoir and means adapted to hold said adjustable end in its adjusted position.
  19. In a liquid dispensing apparatus a reservoir provided with a wall, and an absorbent element having one end located interiorly of said wall and the other end located exteriorly of said wall, the interior end of said element being immersed in said liquid and the exterior end being fixed relatively to said reservoir, and means adapted to maintain tension on said element.
  20. In a liquid dispensing apparatus a reservoir provided with a wall, and a wick element extending over said wall and adapted to conduct liquid from said reservoir, and provided with elastic means tending to yieldingly hold one end of said wick element immersed in said liquid.
  21. In a liquid dispensing apparatus a reser-

- voir provided with a wall, and a wick element extending over said wall and adapted to conduct liquid from said reservoir, and provided with elastic means tending to yieldingly hold one end 5 of said wick element immersed in said liquid, and mechanism adapted to raise a portion of said wick element against the tendency of said elastic means.
22. In a liquid feeding apparatus, a reservoir of liquid provided with a wall, and a plurality of absorbent elements adapted for partial immersion in said liquid and adapted to siphon liquid over said wall, each element being provided with an individual mechanism adapted to adjust the depth 10 of the immersion of said element in the liquid, the portion of said element adapted for immersion gradually varying in cross-sectional area.
23. In a liquid dispensing apparatus, a reservoir of liquid, a plurality of wick elements adapted for immersion in said liquid, a plurality of members each independently vertically adjustable with relation to said liquid, and means associated with each of said members adapted to adjust the depth of immersion of one of said 15 wicks.
24. In a dispensing apparatus, a reservoir of liquid, a member vertically slidably mounted in said reservoir, and an absorbent element adapted to conduct liquid from said reservoir, said member being adapted to control the liquid conducting capacity of said absorbent element.
25. In a liquid feeding device, a reservoir of liquid, a liquid distributing member, a plurality of wicks depending from said reservoir and adapted to transfer liquid from said reservoir to said member, and individual means adapted to independently vary the amount of liquid transferred by each of said wicks, said wicks being spaced one from the other whereby liquid transferred by each wick is prevented from passing to the next adjacent wick.
26. In a dampening device for lithographic presses or the like, a reservoir of liquid, a roller, and an absorbent element adapted to transfer liquid from said reservoir directly to said roller, means for maintaining said element taut and means for preventing the stretching of said element.
27. In a dampening device for lithographic presses or the like, a reservoir of liquid, a member adapted to receive liquid, and a plurality of spaced liquid absorbent elements adapted to transfer liquid, each independently of the other, from said reservoir directly to said receiving member, said elements each having an absorbing end and a delivering end, the delivering ends of said elements being fixed relatively to said member and the absorbing ends of said elements being movably mounted with relation to said member, and individual means adapted to move the absorbing end of each of said elements independently.
28. A liquid feeding device adapted to supply liquid to a lithographic plate, comprising a reservoir of liquid, a plurality of wick elements adapted to absorb liquid and mounted cross-wise of said plate, said wick elements being spaced from each other and each wick element being adapted to feed liquid from said reservoir, and individual means adapted to vary the amount of liquid fed by each element, without affecting the amount of liquid fed by any other element.
29. In a dampening device for a lithographic press or the like, a reservoir of liquid, a liquid transferring member, and a plurality of elements adapted to absorb liquid, one end of each of said elements being immersed in said reservoir and the other end being in contact with said member, said elements being spaced from each other in a direction transversely of the press, and individual means adapted to vary the amount of liquid absorbed by each of said elements.
30. In a dampening device for lithographic presses or the like, a reservoir of liquid, a liquid distributing member, and a plurality of spaced siphon elements, having a liquid raising leg and a liquid lowering leg, each element being adapted independently to transfer liquid from the reservoir to the member, and means adapted to vary the height of the liquid raising leg.
31. In a dampening device for lithographic presses or the like, a reservoir of liquid, a plurality of liquid distributing rollers, a plurality of spaced absorbent elements adapted to have one end immersed in said liquid and each adapted to individually and continuously conduct liquid to one of said distributing rollers, and means adapted to selectively interrupt the flow of liquid through one of said elements.
32. In a dampening device for lithographic presses or the like, a reservoir of liquid, means for maintaining the level of liquid constant, a plurality of liquid distributing rollers, a plurality of wick elements adapted to have one end immersed in said liquid and each forming an individual passage for liquid from said reservoir to one of said rollers, and a plurality of individual means each adapted to vary the depth of immersion of one of said wick elements.
33. In a dampening device, a reservoir of liquid, a roller partially immersed in said liquid, an auxiliary reservoir of liquid and a siphon wick element having one leg partially immersed in said auxiliary reservoir and its other leg in contact with said roller.
34. In a dampening device for lithographic presses or the like, a liquid distributing member, means adapted to substantially uniformly coat said member with liquid, a reservoir of liquid and a plurality of siphon elements each adapted independently to transfer liquid from said reservoir to said coated member, and individual means adapted to control the amount of liquid transferred by each of said siphon elements.
35. In a dampening device, a reservoir of liquid, a roller partially immersed in said liquid, a reservoir of supplementary liquid, and a siphon wick element having one leg partially immersed below the surface of said supplementary liquid and its other leg in contact with said roller, and means adapted to vary the distance from the surface of said supplementary liquid to said roller, measured along said siphon.
36. In a dampening device, a reservoir of liquid, a roller partially immersed in said liquid, an auxiliary reservoir of liquid and a siphon wick element having one leg partially immersed in said auxiliary reservoir and its other leg in contact with said roller and adapted to deposit liquid from said auxiliary reservoir upon said roller, and means for controlling the amount of liquid deposited by said element.

JOSEPH SCHULTZ.
